UNITED STATES PATENT OFFICE.

WILLIAM E. FARRELL, OF LITTLE ROCK, ARKANSAS.

BELT-TIGHTENER.

1,077,339.

Specification of Letters Patent.

Patented Nov. 4, 1913.

Application filed September 16, 1911. Serial No. 649,708.

To all whom it may concern:

Be it known that I, WILLIAM E. FARRELL, a citizen of the United States, residing at Little Rock, in the county of Pulaski and State of Arkansas, have invented new and useful Improvements in Belt-Tighteners, of which the following is a specification.

This invention relates to certain novel and useful improvements in belt tighteners or tensioning devices.

In carrying out my invention, it is my purpose to provide a tensioning device or tightener for belts and the like whereby the belt will be at all times held under tension and furthermore, my improved belt tightener embraces the desired features of simplicity, efficiency and durability and may be manufactured and marketed at a relatively low cost.

20 With the above and other objects in view, the invention consists in the construction, combination and arrangement of parts hereinafter set forth in and falling within the scope of the claim.

25 In the accompanying drawings; Figure 1 is a view partly in end elevation and partly in section showing the frame for the idler pulley of the belt tightener and the tension means therefor. Fig. 2 is a similar view 30 partly in side elevation and partly in section.

35 Referring now to the accompanying drawings in detail, the numerals 13, 13 designate two side bars depending from a top cross bar 14 and forming therewith an inverted U-shaped frame, while 15 indicates a tension roller which is mounted upon a shaft 16, the ends of which latter are journaled in boxes 17 sliding in the side bars 13 of the 40 frame. Each box supports a vertically extending rod 18 preferably cylindrical in form, the lower end of said rod being appropriately fastened to the box as at 19,

while the upper end 20 thereof projects through a threaded sleeve 21 and into the 45 top bar of the frame, this sleeve being adjustable vertically and having a flange 22 which bears against the top end of the spiral tension spring 23, said spring surrounding the rod. By this arrangement, it will be 50 seen that the tension of the idler wheel may be automatically adjusted and by the arrangement of mounting the tension means the proper adjustment is attained at each side of the wheel.

55

In use, any extra strain placed upon the belt causes the tension wheel to rise, thus relieving the pressure on the belt, and when the tension upon the belt relaxes the spring forces the wheel downwardly against the 60 belt thus increasing the tension thereon to take up any slackness that might otherwise be present in the belt.

I claim:

A belt tightener or tensioning device comprising an inverted U-shaped frame formed of a top cross bar and side bars depending therefrom and spaced apart, axially alining boxes carried by said side bars and slidably therein, a shaft journaled in said boxes, a 65 pulley upon said shaft, a rod extending from each box parallel with the respective side bar, sleeves threaded into said connecting bar for receiving the free ends of said rods, and springs surrounding said rods and each 70 having one end bearing upon the respective box and the opposite end in contact with the sleeve whereby the tension of the spring 75 may be adjusted.

In testimony whereof I affix my signature in presence of two witnesses.

WILLIAM E. FARRELL.
